SINKER HEAD FOR FULL-FASHIONED
KNITTING MACHINESWalter M. Golaszewski and Anthony Kaczor,
Philadelphia, Pa.

Application January 19, 1946, Serial No. 642,372

1 Claim. (Cl. 66—110)

1

This invention relates to a sinker head of the type used in flat, or full fashioned hosiery knitting machines.

One object of the invention is to produce an improved sinker head of the type set forth.

A sinker head of the type under consideration is provided with apertured lugs, by means of which it is secured to the bedplate or frame of the machine and with end, pendant bearing members in which the trunnions of the knock-over bit are journaled. The pendant bearing members referred to have thus far been formed as integral parts of the sinker head. This increased the difficulty of accurately machining the head and, if either the head or the bearing member wore out or suffered damage, it was necessary to discard the entire sinker head.

It is, therefore, a further object of this invention to produce an improved sinker head in which the bearing members referred to are made separate from and are firmly but detachably secured to the sinker bar, thus facilitating machining and permitting replacement of the sinker head or the bearing members independently of one another.

These and other objects are attained by the invention as set forth in the following specification and the accompanying drawings, in which:

Fig. 1 is a perspective, composite or exploded view showing the various parts of a sinker head embodying the invention;

Fig. 2 is an enlarged section on line 2—2 of Fig. 1, with the parts all assembled;

Fig. 3 is a section on line 3—3 of Fig. 1, with the parts all assembled; and

Fig. 4 is a section on line 4—4 of Fig. 1, with the parts all assembled.

The sinker head illustrated includes a body portion 10 which is cut down in thickness as compared with the end portions 11, so as to provide a recess for receiving a detachable insert bar 12 which has machined therein grooves 13 for guiding the sinkers in their movement transversely of the bar. The bar may be secured to the sinker by any suitable means, such as countersunk screws, but it is preferred to solder or braze the insert bar to the sinker head. The sinker head is provided with end lugs which are provided with countersunk apertures 14 for the passage of screws by means of which the sinker head may be attached to the bedplate of the knitting machine.

In order to provide bearings for the trunnions of the knock-over bit, it has heretofore been the practice to form pendant bearing members which were integral with the end portions 11 of the sinker head. Such members were difficult to machine and also increased the difficulty in machining of the sinker head itself. According to this invention, the pendant bearing members are formed entirely separate from the sinker head. As shown, the undersides of the end portions

of the sinker head are provided with recesses 15 which are adapted to receive pins 16 formed at the upper ends of the pendant bearing members 17, each of which constitutes one-half of a complete bearing. The other halves of the bearings are in the nature of separate members 18 which are adapted to be detachably secured to the halves 17 by means of screws 19 passing through apertures 20 in the halves 17 and 18, as shown in Fig. 2. The pins 16 are soldered or brazed in the recesses 15 so as to firmly secure the bearing members 17 while permitting the same to be removed by the application of heat. By this means, the machining of the sinker head and of the bearing members is facilitated and if it is necessary to discard the sinker head or the bearing members, the bearing members can be readily disengaged from the sinker head. The separable insert bar 12 is machined separately and is provided with a pendant shoulder 21 extending the entire length of the bar and adapted to abut the edge 22 of the sinker head to locate the insert bar relative to the sinker head.

When it is desired to remove the bar insert 12 or the pendant bearing members 17, it is merely necessary to apply heat sufficient to melt the metal which forms the bond between these parts and the sinker head.

What is claimed is:

30 A sinker head including end portions having apertures therein for receiving fastening means for securing said head to the bedplate of a knitting machine, and an intermediate body portion of a reduced thickness, a separate bar secured by metal fusion to one face of said body portion and having grooves for guiding the sinkers of the knitting machine, there being apertures in said end portions, pendant bearing members for engaging the trunnions of a knock-over bit forming part of the knitting machine, and pins carried by said bearing members and secured by metal fusion in said recesses to secure said bearing members to said end portions.
